PLASTIC BOTTLE

Fulton W. Hallowell, Jr., 22 Plumbridge Drive,
Levittown, Pa.

Filed June 12, 1964, Ser. No. 80,373

Term of patent 14 years

(Cl. D58—6)

FIG. 1 is a top perspective view of a plastic bottle showing my new design;

FIG. 2 is a top plan view thereof;

FIG. 3 is a side elevational view thereof, and

FIG. 4 is a fragmentary cross-sectional view thereof taken on line 4—4 of FIG. 2.

The characteristic feature of my design resides in the upper neck portion which includes a straight-sided, downwardly converging, frusto-conical section merging at its lower end with the upper end of a downwardly diverging, frusto-conical portion, all as shown.

I claim:

The ornamental design for a plastic bottle, as shown and described.
